UNITED STATES PATENT OFFICE.

BARTHOLOMEW JULIEN, OF OMAHA, NEBRASKA, ASSIGNOR OF ONE-HALF TO CHARLES E. FULLER, OF OMAHA, NEBRASKA.

DOOR LOCK.

Application filed January 31, 1921. Serial No. 441,113.

To all whom it may concern:

Be it known that I, BARTHOLOMEW JULIEN, a citizen of the United States, residing at Omaha, in the county of Douglas and State of Nebraska, have invented a certain new and useful Improvement in Door Locks, of which the following is a full, clear, concise, and exact description, reference being had to the accompanying drawings, forming a part of this specification.

This invention relates to improvements in door locks, and more specifically to door locks employed in connection with horizontally slidable doors such as are found on freight, mail, baggage, express and street cars, in buildings, ships and other places.

One object of the invention is to provide a door lock which may be easily manipulated to render it both operative and inoperative and wherein the construction is simple, comparatively inexpensive, and comprised of few parts.

Another object of the invention is to provide a device which will positively hold the door in closed position and lock it and which will positively prevent accidental opening of the door which might otherwise occur as a result of the door being subject to jarring or vibration as for instance on a moving body such as a railway or street car.

A still further object of the invention is to provide a door locking device which, in operative position, will prevent pilfering or prying open of the door without leaving visual evidence thereof.

Another object of the invention is to provide a door locking device which will readily accommodate itself to such variations as may occur in the manufacture and assembling of the parts and to such distortion as may occur in service.

The invention furthermore consists in the improvements in the parts and devices and in the novel combinations of the parts and devices herein shown, described and made the subject matter of claim.

In the drawings forming a part of this specification, Figure 1 is a side elevation of a portion of a freight car showing my improvements employed in connection with the usual side door of such a car, parts being broken away in order to better accommodate the figure on the sheet. Figure 2 is an enlarged elevational view of the door locking device proper shown in Figure 1. In Fig-

ure 2, the dotted lines indicate the inoperative or open position of one of the door locking elements. Figure 3 is a horizontal, sectional view corresponding substantially to the line 3—3 of Figure 2. Figure 4 is a horizontal, sectional view upon a larger scale and corresponding substantially to the line 4—4 of Figure 2. Figure 5 is an elevational view of the fulcrum or bracket member shown in Figures 1, 2 and 3. Figure 6 is a view similar to Figure 2 illustrating another embodiment of my invention. Figures 7 and 8 are views similar to Figures 3 and 4 and corresponding to the section lines 7—7 and 8—8, respectively, of Figure 6. And Figure 9 is a vertical, sectional view corresponding to the section line 9—9 of Figure 6.

Referring first to the construction illustrated in Figures 1 to 5, inclusive, the side wall of a car is indicated at 10, said car being provided with the usual side door opening as indicated at 11 in Figure 3. Said opening 11 of the car is adapted to be closed in the usual manner by a horizontally slidable door 12. In the instance shown, said door 12 is supported at its top edge by roller-carrying brackets 13—13, the rollers of which travel upon a suitable track 14. The bottom edge of the door is guided and confined by suitable brackets 15—15 secured to the lower edge of the car side, the door preferably having small castings 16—16 secured thereto at its bottom edge adapted to engage the brackets 15. As will be understood by those skilled in the art, the door 12 is in closed position as illustrated in all of the figures and the rear edge of the door is at the right as viewed in Figure 1.

In carrying out my invention, I employ, broadly, a bracket or fulcrum A secured to the side wall of the car; a pivoted element or lever B, mounted on the bracket A; a locking element C rigidly secured to the car door 12 at the lower rear corner thereof; and a slideable bolt or seal pin D carried by the lever B.

The fulcrum or bracket A, preferably in the form of a malleable casting, is suitably rigidly secured to the side wall of the car at a point below the lower edge of the door and a short distance rearwardly of the rear edge of the door when the latter is in closed position, as best shown in Figures 1 and 2. Said bracket A is provided with a substantially centrally disposed perforated boss 17 in

which is received a pivot pin 18 preferably in the form of a rivet. To the side of the boss 17 farthest from the door and in alignment with the boss, the bracket A is formed 5 with an integral shoulder or shelf 19 the function of which will appear hereinafter. Below the boss 17, the bracket A is formed with a vertically disposed integral shoulder 20 adapted to cooperate with a shoulder 21 10 formed on the adjacent end of the lever element B, as shown in Figure 2.

The lever element B is pivotally attached to the bracket A by said pivot pin 18. The lever B is provided, however, with an 15 elongated opening 22 through which the pivot pin extends so as to adapt the lever B for vertical movement with respect to the pivot pin when in the position illustrated in Figure 2 so that the lever B may be lifted 20 sufficiently to have the lug 21 thereof clear the lug 20 of the bracket A and thereby permit the lever B to be swung in a clockwise direction to the inoperative position shown in Figure 2 at B^x.

25 At its upper or free end, the lever B is deflected slightly outwardly from the side wall of the car so as to bring it into alignment with or same plane as the rear edge of the door, as shown in Figures 3 and 4. At its 30 said free end, the lever B is provided with a rib 23 and a downwardly flaring undercut groove 24 which are adapted to cooperate with a corresponding slot 123 and rib 124 formed on the adjacent end of the locking element C. As best shown in Figure 2, the 35 opposing faces of the ribs and grooves 23, 123; 24, 124 are inclined from the vertical in the general direction from the front upper corner of the door toward the rear lower corner. With this arrangement, it is evident 40 that the lever B may be swung in a counter-clockwise direction into engagement with the locking element C and vice versa and, when the two elements are in abutting 45 engagement, they are interlocked. Any tendency of the door 12 to shift in an opening direction, i. e., toward the pivot or fulcrum of the lever B, will place the lever B under compression.

50 As will be clear from the preceding, the operative end of the locking element C is disposed on the rear edge of the door 12 near the bottom thereof, although the main part of said element C, indicated at 25, is extended horizontally over the outer side of 55 the door and rigidly secured thereto by any suitable means such as the bolts 26. In order to obtain a more extended and secure fastening to the door, a horizontally extending strap 27 may be employed forming in effect 60 an extension of the element C, there being a common bolt for both as indicated at 26' in Figure 3.

In the construction illustrated, I have 65 shown the bolt D as slidably mounted on the

lever B. Any suitable means may be employed for so slidably mounting the bolt D, that shown in the drawing comprising a pin 28 carried by the lever, the same working in an elongated horizontally extending slot 29 70 formed in the bolt D. The bolt D may be guided by an overhanging flange 30 and a lower lug 31 carried by the lever B. The end of the bolt D at the left, as viewed in Figures 2, 3 and 4, is preferably tapered as indicated at 32 so as to facilitate its insertion through a horizontal slot 33 formed in an outwardly extending triangular shaped lug 34 made integral with the element C. With the bolt D positioned within the slot 33, as 80 shown in the drawing, it is evident that the lever B cannot be disengaged from the locking element C. Where my locking device is employed on a railroad car, it is desirable to provide means for the use of the usual lead seal and to this end the bolt D has a small lug 35 thereon slotted as indicated at 85 36 in alignment with a corresponding slot 37 formed in the lug 34. The usual lead seal may be run through the slots 36 and 37, such 90 a seal being indicated conventionally at 38 in Figure 4.

In some instances, it is desirable to utilize a padlock or the like in order to prevent tampering and to provide for this contingency, the lever B and bolt D are provided with horizontally extending flanges 39 and 40 respectively, having openings 41 therein adapted to be aligned when the parts are in operative position, it being evident that the 100 padlock may be inserted through said aligned openings 41 and thereby positively prevent disengagement of the bolt D from the element C without first removing the padlock.

Any tendency of the door to move in an 105 opening direction, i. e., toward the right as viewed in Figures 1 and 2, will be resisted by the lever B being prevented from rotating in a clockwise direction because of the engagement of the shoulder 21 thereon with the shoulder 20 of the fulcrum or bracket A. To open the door, it is first necessary to disengage the bolt D from the element C then lift the lever B so as to clear the lug 21 from the lug 20 and then swing the lever B clear 110 of the path of the door to the position indicated by dotted lines B^x in Figure 2. To hold the lever B in its inoperative position shown and to prevent it from swinging 115 promiscuously, the lever B is preferably provided with a lug 42 on its inner side, which will engage the ledge or shelf 19 so as to sustain the weight of the lever. An additional lug 43 may also be provided on the lever B adapted to engage the lug 20 of the bracket 120 A simultaneously with the engagement of the lug 42 with the shelf 19 so as to thereby afford a double support for the lever in its 125 inoperative position.

Referring next to the construction shown 130

in Figures 6 to 9 inclusive, I employ a fulcrum or bracket member A'; a locking lever or element B'; a locking element C'; a slideable bolt D'; and an additional vertically 5 slideable bolt or latch E carried by the element C'.

The bracket A' is or may be the same as the bracket A and has a horizontal shoulder or ledge 119 and vertical shoulder or lug 120. The lever B' is substantially the same as the lever B except that it is not provided with any lug corresponding to the lug 21 and furthermore, the opening therein through which the pivot pin 118 extends is not elongated, thereby dispensing with vertical shifting of the lever B in order to disengage it from the lug 20. The lever B' has lugs 143 and 142, the same as in the previously described construction adapted to 10 cooperate with the ledge 119 and lug 120, respectively. The engaging faces of the lever B' and element C' are preferably the same as in the case of the construction shown in Figures 1 to 5. The bolt D' is also mounted 15 on the lever B' in substantially the same way and it and the lever B' are provided with similar means for accommodating a padlock. Detailed description of these features is not deemed necessary.

The locking element C' is formed with an outwardly extended integral lug 134 having a horizontally extending opening 133 therein to accommodate the bolt D'. The latter is 20 preferably enlarged near its lefthand end 25 as viewed in Figure 8, as indicated at 50 so as to provide sufficient metal to permit of the bolt being vertically slotted or notched as indicated at 51, said notch being located to the left of the lug 134 when the parts are 30 in operative position. Said notch 51 is disposed in alinement with the lower end 52 of the latch E which is vertically slidably 35 mounted on an upwardly extended part 53 of the locking element C' as by means of 40 the rivet 54 and elongated slot 55. The lower end of the latch E may be guided in 45 a perforated flange 56 formed on the element C'. At its lower end, the latch E is slotted as indicated at 57, said slot being 50 disposed below the bolt D' when the parts are in locked position so as to receive a sealing strip 58 and thereby prevent unlocking 55 of the parts without leaving visual evidence thereof.

I have herein shown and described what I now consider the preferred manner of carrying out the invention but the same is merely illustrative and I contemplate all changes and modifications that come within 60 the scope of the claims appended hereto.

I claim:

1. In a door locking device, the combination with a member having a door opening therein and a door for closing said opening, 65 said door being lineally movable from open

to closed position and vice versa; of a locking element pivotally mounted on said member at a point outside of the path of movement of the door and to the rear thereof when the door is in closed position, and arranged to swing in a plane parallel to the door, the free end of said element, when in operative position, extending toward the rear edge of the door; a cooperable locking element secured to said door at its rear edge 70 and in line to engage said free end; cooperating ribbed and grooved abutting faces on said elements preventing relative movement perpendicularly to the door; and a locking bolt slidably mounted on one of said 75 elements, the other of said elements having an opening into which an end of said bolt is adapted to be positioned when the parts are in operative position whereby to prevent the pivoted element from swinging 80 about its pivot.

2. In a door locking device, the combination with a member having a door opening therein and a door for closing said opening, 85 said door being lineally movable from open to closed position and vice versa; of a lever pivotally mounted on said member at a point outside of the path of movement of the door and at the rear thereof when the door is in closed position, the free end of said 90 lever, when in operative position, extending toward the rear edge of the door; a cooperable locking element secured to said door at its rear edge and in line to engage the free 95 end of said lever; cooperating abutting faces on said lever and element; and a locking bolt movably mounted on said lever, said element having an opening therein into 100 which a part of said bolt is adapted to be positioned when the parts are in operative 105 relation whereby to prevent said lever from being swung about its pivot.

3. In a door locking device, the combination with a member having a door opening therein and a door for closing said opening, 110 said door being lineally movable from open to closed position and vice versa; of a locking element pivotally mounted on said member at a point outside of the path of movement of the door and to the rear thereof 115 when the door is in closed position and arranged to swing in a plane parallel to the door, the free end of said element, when in operative position, extending toward the rear edge of the door; a cooperable locking 120 element secured to said door at its rear edge and in line to engage said free end; cooperating abutting faces on said elements; and a locking bolt slidably mounted on one of said elements, the other of said elements 125 having an opening into which an end of said bolt is adapted to be positioned when the parts are in operative position whereby to prevent the pivoted element from swinging about its pivot, said bolt and said element 130

having the opening to accommodate said bolt being provided with adjacent slots adapted to receive a sealing band.

4. In a door locking device, the combination with a member having a door opening therein and a door for closing said opening, said door being lineally movable from open to closed position and vice versa; of a lever pivotally mounted on said member at a point outside of the path of movement of the door and at the rear thereof when the door is in closed position, the free end of said lever, when in operative position, extending toward the rear edge of the door; a cooperable locking element secured to said door at its rear edge and in line to engage the free end of said lever; cooperating abutting faces on said lever and element; and a locking bolt movably mounted on said lever, said element having an opening therein into which a part of said bolt is adapted to be positioned when the parts are in operative relation whereby to prevent said lever from being swung about its pivot, said bolt and locking element being both provided with slots adapted to accommodate a sealing band.

5. In a door locking device, the combination with a member having a door opening therein and a door for closing said opening, said door being lineally movable from open to closed position and vice versa; of a bracket secured to said member and located adjacent to but at the rear of and below the door when the latter is in closed position, said bracket having a shoulder thereon; a locking element pivotally mounted on said bracket at a point below the door to swing in a plane parallel to the door, the free end of said element, when in operative position, extending upwardly toward the rear edge of the door; a cooperable locking element secured to the door at its rear edge and in line to engage said free end; cooperating abutting faces on said elements; means for locking said elements when in operative engagement and to prevent pivotal movement of said first named element; and a shoulder on said pivoted element adapted to engage with said shoulder on the bracket to sustain the pivoted element when it is swung to inoperative position below the door.

6. In a door locking device, the combination with a member having a door opening therein and a door for closing said opening, said door being lineally movable from open to closed position and vice versa; of a locking element pivotally mounted on said member at a point outside of the path of movement of the door and to the rear thereof when the door is in closed position, the free end of said element, when in operative position, extending toward the rear edge of the door; a cooperable locking element secured to said door at its rear edge and in line to engage said free end; cooperating

abutting faces on said elements; a locking bolt slidably mounted on one of said elements, the other of said elements having an opening into which an end of said bolt is adapted to be positioned when the parts are in operative position whereby to prevent the pivoted element from swinging about its pivot; and cooperating flanges on one of said elements and said bolt having perforations therein adapted to be brought into alinement when the parts are in operative position, said perforations being adapted to accommodate a padlock or the like whereby to prevent disengagement of the parts.

7. In a door locking device, the combination with a member having a door opening therein and a door for closing said opening, said door being lineally movable from open to closed position and vice versa; of a locking element pivotally mounted on said member at a point outside of the path of movement of the door and to the rear thereof when the door is in closed position, the free end of said element, when in operative position, extending toward the rear edge of the door; a cooperable locking element secured to said door at its rear edge and in line to engage said free end; cooperating ribbed and grooved interlocking abutting faces on said elements; inclined in a general direction upwardly and from the point of pivotal support for said first named locking element; and means for preventing accidental disengagement of said pivoted element from the second named element.

8. In a door locking device, the combination with a member having a door opening therein and a door for closing said opening, said door being lineally movable from open to closed position and vice versa; of a bracket secured to said member and having a lug thereon; a lever pivotally mounted on said bracket, said lever having a lug adapted to cooperate with the lug of said bracket when the lever is in operative position to thereby prevent rotation of said lever about its pivot in an opening direction, said lever being additionally movably mounted with respect to the bracket to a position where the lug thereof clears the lug of the bracket to thereby permit rotation of said lever in an opening direction; a cooperable locking element secured to said door, said element and lever having cooperating engaging faces; and means for preventing disengagement of said cooperating faces comprising an apertured lug and a slidable bolt.

9. In a door locking device, the combination with a member having a door opening therein and a horizontally slidable door adapted to close said opening; of a fulcrum bracket secured to said member at a point below the door and at the rear of the rear edge thereof when the door is in closed position,

- said fulcrum bracket having a plurality of shoulders thereon; of a locking element secured to said door adjacent the lower rear corner thereof; a lever pivotally mounted 5 on said fulcrum bracket, said lever having a plurality of shoulders, one of which is adapted to engage with one of the shoulders of the fulcrum bracket when the lever is in operative position to thereby prevent pivotal movement of said lever in an opening direction, said lever being additionally shiftable with respect to its pivot so as to disengage said shoulders, another of said shoulders on the lever being adapted to engage 10 another of said shoulders of the fulcrum bracket when the lever is in inoperative position to thereby sustain the lever; a bolt slidably mounted on said lever, said locking element having an apertured lug within which said bolt is adapted to be inserted 20 when the parts are in operative position to thereby prevent disengagement of the lever from the locking element.
- 15 In witness that I claim the foregoing I have hereunto subscribed my name.

BARTHOLOMEW JULIEN.
